COLLAPSIBLE RAILING FOR UTILITY TRUCK TOWER PLATFORM

Herman J. Treche, Fairview Park, and James Howard Holan, Rocky River, Ohio, assignors to J. H. Holan Corporation, Cleveland, Ohio, a corporation of Ohio

Application September 16, 1950, Serial No. 185,268

4 Claims. (Cl. 304—38)

The invention relates to hydraulic towers and particularly to mechanism of this character designed for heavy duty. The tower includes a plurality of telescoping units which can be extended to various selective working heights, and can be collapsed into a comparatively short height.

Although the tower is designed for use on any suitable support, it is particularly designed for use with a utility truck body, and the invention is illustrated by a description herein and a showing thereof in the accompanying drawings as applied to a utility truck chassis. An important use of utility truck bodies is in the installation and maintenance of public utility facilities.

The instant improved tower is raised and lowered by hydraulic mechanism, its functions are electrically controlled, and the controls are hooked-up with the truck engine and battery.

Included amongst the objects and advantages of the invention in hydraulic towers herein presented are the following:

The tower is installed at a comparatively low initial investment, and is easy to install and maintain.

The tower consists of a comparatively small number of unit assemblies which are easily replaced.

The tower is available in a number of servicing heights, for instance, total heights from about 17 feet to about 30 feet, and has a low collapsed height which provides ample clearance for underpasses and garage parking. The working platforms forming part of the tower are of various types, stationary, rotary, and transversely movable, all of which are improved structures and are herein shown and described.

A push-button control governs the hydraulic system, and is so positioned as to eliminate the necessity of workmen bending over to operate it. There are multiple sets of electrical controls for convenient operation located at various points, for instance, in the truck cab, on the truck body, and on the working platform of the tower.

The controls permit stopping of the tower movement at any height, and an emergency manual control is provided for use in the event of engine failure when the tower is elevated.

The tower is provided with an automatic engine speed regulator, thus eliminating the necessity of manual control from the cab for this purpose, this automatic regulator insuring proper tower and engine speeds at all times.

The tower includes an improved metering device which, without the necessity of manually-actuated valves or control rods, insures an approximately constant tower speed while raising and lowering the tower, and provides low maintenance cost. Any suitable tower speed can be provided as desired.

Mounting of the tower on a utility truck is provided within a minimum of truck space, the installation requiring only about fourteen inches, longitudinally measured, from the back of the truck cab to the rear end of the supporting channels of the tower.

The tower includes a floating hydraulic cylinder which

2

acts to lift and lower the platform. Side thrusts on the packing glands of the hydraulic cylinder are eliminated, thus minimizing oil leaks.

5 The tower is provided with telescoping frame sections within which telescoping cylindrical mast units forming the floating hydraulic cylinder are enclosed, which frame sections are of the box type and provide a maximum of strength and stability. These box sections are provided with interior adjustable wear plates.

10 All tower platforms are insulated to a comparatively high voltage.

The tower is adaptable to various types of utility truck chassis, such adaptation being hereinafter illustrated.

15 The structure has railings for the working platform of the tower that are of comparatively great heights, thus making for greater safety of the operators.

20 Certain improvements and benefits attach to the types of platforms utilized, for instance, a counter-balance railing assembly is provided for the rotating platform, and the transversely-movable type of platform is hydraulically operated.

25 The instant invention is directed to the attainment of the above and also certain related objects which will be hereinafter mentioned, all as hereinafter fully described in detail and shown in the accompanying drawings.

The claims of the instant application are directed to the railing structure utilized upon the rotary platform.

30 The tower will be hereinafter referred to as having its front immediately to the rear of the truck cab, and the respective left and right sides of the tower will be thus referred to as if viewing the tower from the rear.

35 The annexed drawings and the following description set forth in detail certain means illustrating the improvements in hydraulic towers, such means constituting, however, only a few of the various forms in which the principle of the invention may be embodied.

In said annexed drawings:

40 Figure 1 is a left side elevation of the hydraulic tower mounted with a truck body upon the chassis of a utility truck, this figure showing the tower in lowered position and including a stationary type of upper working platform;

45 Figure 2 is a rear elevation of the tower elements shown in Figure 1, the truck body being suggested by dot-and-dash lines;

50 Figure 3 is a rear elevation of the improved tower in a raised position and includes a transversely-movable type of platform, the latter being shown in full lines in extreme moved position, the figure also including, in dot-and-dash lines, a suggestion of the platform in normal position, and a suggestion of another type of truck body to the particular chassis of which the tower has been adapted, the distance P—P indicating the overall working field of the platform, and the distance R—R indicating the distance through which a certain platform frame part 55 has moved during the movement of the platform from the dot-and-dash position to the full-line position;

55 Figures 4 and 5 together constitute a broken top plan, upon an enlarged scale, of the transversely movable working platform, the actuating elements therefor, and the mast and frame units, the respective Figures 4 and 5 being taken from the plane indicated by the lines 4—4 and 5—5, Figure 3, the transversely movable platform being shown in full lines in extreme moved position and, in dot-and-dash lines, in closed or normal position;

60 Figure 6 is a left side broken and fragmentary elevation, upon an enlarged scale, at the platform level of the tower, taken from the plane indicated by the line 6—6, Figure 3;

65 Figure 7 is a broken transverse vertical section, looking toward the front, taken in the plane indicated by the line 7—7, Figure 6, and particularly showing a concentric

series of telescoping mounting tubes and a pair of telescoping track sections forming part of the platform-actuating means;

Figure 8 is a view similar to Figure 7 but showing particularly the hydraulic cylinder structure utilized for transversely moving the working platform, the view being taken in the plane indicated by the line 8—8, Figure 6;

Figure 9 is a broken fragmentary transverse top plan section, taken in the plane indicated by the line 9—9, Figure 6, showing particularly a pair of relatively telescoping track sections;

Figure 10 is a fragmentary longitudinal vertical section, upon an enlarged scale, looking toward the right, and taken in the planes indicated by the line 10—10, Figure 5, the view particularly showing the working floor of the platform, and platform-moving structures including one of a pair of sheaves forming part thereof;

Figure 11 is a transverse vertical section, upon an enlarged scale, looking toward the front, and taken in the plane indicated by the line 11—11, Figure 5, this view being a further showing of the sheave and some related structures;

Figure 12 is a broken top plan view of the sheaves and some related structures shown in Figures 4, 5, and 11, the sheave positions being intermediate those shown therefor in Figures 4, 5, and 11;

Figures 13 and 14 together constitute a transverse vertical section, upon an enlarged scale, and looking toward the front, of the vertically-movable telescoping mast and frame units of the tower in lowered position, the figures particularly illustrating the telescoping features of the mast and frame units and being taken in the plane indicated by the line 13—14 and 13—14, Figure 4;

Figure 15 is a top plan section of the telescoping mast and frame units, taken in the planes indicated by the line 15—15, Figure 13;

Figure 16 is an elevation, upon an enlarged scale, of a portion of an oil-metering valve and some related elements whose function appears more in detail in a diagram constituting Figure 23;

Figure 17 is a side elevation, upon an enlarged scale, of the railing for the transversely movable platform 7 shown in Figure 3, the railing being up in operative position, a partially folded position and a fully folded position of transverse front and rear railing members being shown in dot-and-dash lines;

Figure 18 is a fragmentary top plan of a front top corner of the railing, the view being on an enlarged scale and taken from the plane indicated by the line 18—18, Figure 17;

Figure 19 is a fragmentary vertical transverse section, taken in the plane indicated by the line 19—19, Figure 18, a free position of a locking plate for certain railing elements being suggested by dot-and-dash lines;

Figure 20 is a fragmentary top plan of the rear top corner of the same side of the railing, the view being on an enlarged scale and taken from the plane indicated by the line 20—20, Figure 17;

Figure 21 is a fragmentary transverse elevation, looking toward the rear, of a bottom corner of the railing, the view being on an enlarged scale and taken from the plane indicated by the line 21—21, Figure 17;

Figure 22 is a fragmentary longitudinal vertical section, taken in the plane indicated by the line 22—22, Figure 21;

Figure 23 is a diagram of the hydraulic system and the electric control for actuating the vertical telescoping units of the tower and the transversely-movable platform, the units of a certain oil-flow control valve being shown in respective neutral positions;

Figure 24 is a top plan of a rotary type of platform and its railing, the latter being up in operative position;

Figure 25 is a side elevation of the elements shown in Figure 24, certain portions of the railing being shown by dot-and-dash lines in collapsed condition;

Figure 26 is a side elevation of certain of the railing

parts shown in Figures 24 and 25 in partially collapsed condition;

Figure 27 is a fragmentary transverse elevation, upon an enlarged scale, taken from the plane indicated by the line 27—27, Figure 25;

Figure 28 is a fragmentary plan section of an upper rear corner of the railing, the view being upon an enlarged scale and taken from the plane indicated by the line 28—28, Figure 25;

Figure 29 is a fragmentary vertical transverse section, upon an enlarged scale, taken from the plane indicated by the line 29—29, Figure 25;

Figure 30 is a fragmentary transverse vertical section, upon an enlarged scale, taken in the plane indicated by the line 30—30, Figure 24;

Figure 31 is a fragmentary longitudinal horizontal section, upon an enlarged scale, taken in the plane indicated by the line 31—31, Figure 25;

Figure 32 is a detail transverse vertical section, upon an enlarged scale, taken in the plane indicated by the line 32—32, Figure 25;

Figure 33 is a fragmentary front elevation taken from the plane 33—33, Figure 24;

Figure 34 is a detail of a certain manually-actuated and emergency operating means;

Figure 35 is an axial section, upon an enlarged scale, of a certain oil-flow control unit of the control valve shown in Figure 23, this control valve unit passing oil to and from the vertically-movable tower mast and the oil reservoir, the parts of this control valve unit of this Figure 35 being in position to pass oil from the reservoir to the mast;

Figure 36 is a section similar to Figure 35 in which the parts of this control valve unit are in position to pass oil from the mast to the reservoir;

Figure 37 is an axial section, upon an enlarged scale, of a certain oil-flow control valve unit which passes oil to and from the reservoir and a hydraulic cylinder for actuating the transversely-movable working platform, the parts of this control valve unit of this Figure 37 being in position to pass oil from the reservoir to the cylinder; and

Figure 38 is a section similar to Figure 37 in which the parts of this control valve unit are in a position to pass oil from the hydraulic cylinder to the reservoir.

Referring to the annexed drawings in which the same parts are designated by the same respective numbers in the several views, a cab 1 and a body 2 of a utility truck are shown in Figures 1 and 2, upon the chassis 14 of which the improved tower having a fixed type 6 of working platform is mounted. The platform 6 is supported by a base 15 secured to the tower frame 5 and the platform 6.

Figure 3 shows the improved tower mounted upon a different type chassis 14¹ carrying a body 2¹. Furthermore, the tower shown in Figure 3 is provided with a transversely-movable platform 7, the mast 4 and frame 5 being elevated and the platform 7 being shown in extended position with its railing 73 up, the normal position of the platform 7, preparatory to moving the platform 7 transversely, being shown by the dot-and-dash outline of the raised railing 73.

The tower is mounted upon the longitudinal side channels 3 of the chassis 14 or 14¹, Figures 1, 2, 3, and 15; Figure 3 indicating one way in which the height of the mounting can be adjusted so as to meet the conditions presented by various types of chassis.

The vertically extensible tower unit comprises, broadly, a plurality of telescoping cylinders constituting an inner mast or floating hydraulic chamber designated by the general number 4, Figures 2, 3, 6, 13, 14, 15, and 23, and a plurality of reinforced telescoping two-part side channels constituting an outer frame designated by the general number 5, Figures 1, 2, 3, 4, 6, 13, 14, 15, 16, and 23. These mast and frame units are combined with an upper fixed horizontal working platform designated by

the general number 6, such as is illustrated in Figures 1 and 2, or a transversely-movable working platform designated by the general number 7, such as is illustrated in Figures 3, 4, 5, 6, 7, and 17, or a rotary working platform designated by the general number 8, such as is illustrated in Figures 24 to 33, inclusive.

The operating and control assembly comprises a hydraulic system designated by the general number 9, Figures 3, 4, 6, 8, 14, 15, 16, 17, and 23, including an oil tank 10, Figures 2, 3, 14, 15 and 23 on the right side of the tower base, a hydraulic cylinder 154, Figures 4, 6, and 8, and a pump 11 at the front, Figures 14, 15, and 23; also an electrical assembly designated by the general number 12, Figures 4, 5, and 23, such electrical assembly 12 including a control housing 13, Figures 2, 3, 14, and 15, on the left side of the tower base. Various electric switch stations are indicated, such as station 16 of the working platform 7, Figures 3 and 17. Further switch stations, not shown, are available in the cab 1 and on the body 2.

Referring particularly to Figures 1, 2, 3, 14, and 15, front and rear transverse tower base channels 21 are provided which are secured directly to the top of the longitudinal chassis channels 3, as shown in Figure 2, or, to accommodate various types of chassis, are secured thereto by depending angles 23, Figure 3, whose flanges are bolted to the cross channels 21, whose webs are bolted to the longitudinal chassis channels 3, and whose bottom ends are secured to the chassis 14. The angles 23 are of a length and design according with the type of chassis upon which the tower is mounted. The bottom of the tower is located about fourteen to fifteen inches from the ground and the tower cross channels 21 are mounted on the longitudinal channels 3 of the respective chassis so as to provide about this height for the bottom of the tower. Cross angles 25 are bolted to the cross channels 21, Figure 15, and at their right ends are welded to the front and rear of the tank 10. Tank bracing angles 22, Figure 15, are welded to the tank 10 and bolted to the cross channels 21. On the left side of the tower a channel 26 is welded to the control housing 13 which housing is mounted on the cross channels 21 and secured to the truck frame, Figure 15, or the control housing 13 may be otherwise suitably secured. A front cross channel 28, Figures 14 and 15, is welded to the longitudinal chassis channels 3 and supports the pump 11. Referring particularly to Figure 3, gussets 29 are welded to the bases of the webs of the respective outer channel units of the telescoping frame 5 and to the top of the cross channels 21.

Other base connecting and strengthening members are utilized as are required by the size and type of tower and type of chassis.

Structure of the mast and frame

The mast 4 includes five telescoping cylindrical vertical units, Figures 6, 13, 14, and 15, designated respectively, reading from the outside toward the inside of the mast 4, by the numbers 31, 32, 33, 34, and 35, which five units make up a floating hydraulic cylinder. The outer mast unit 31 is stationary and has a base plate 36 secured by a bottom mast ring 37 which is bolted to and above side extensions 36¹ of the base plate 36, Figure 15, and welded to the exterior surface of the outer cylinder 31. The base plate extensions 36¹ are secured by bolts 39 adjacent their outer ends to the tower cross channels 21. An oil seal ring 38 adjacently surrounds the bottom of the outer mast unit 31 and is embedded in and at the bottom of the ring 37.

Adjacent the lower ends of the cylinders 31, 32, 33, 34, and 35, and between each adjacent two cylinders, are bearings 40, Figure 14, providing for the sliding of the four inner cylinders upon the respectively adjacently exterior cylinders. Externally extending from each of the four inner cylinders and seated in the respective cylinders adjacently above the bearings 40 are an external type of

split stop rings 43. Adjacently below the bearings 40 are also similarly positioned another like series of an external type of split stop rings 42. Adjacently below this last-mentioned series of stop rings are a series of three internal type of split stop rings 41 which are seated in the three cylinders 32, 33, and 34 and extend inwardly of the respective cylinders. Materially above the rings 43 is a series of an external type of split stop rings 44 projected outwardly from the four inner cylinders 32, 33, 34, and 35. Fluid relief holes 45 are drilled through the four inner cylinders 32, 33, 34, and 35 above the top series of stop rings 44.

The function and operation of the several series of stop rings will be hereinafter fully described.

A sloping cap 49, Figures 6 and 13, for the interior cylinder 35 is welded thereto and has a depending portion 49¹ securely engaging by its periphery the inner wall of the inner cylinder 35. A bolt and nut combination 51 also secures the cap 49 to the top of the inner cylinder 35, the bolt being an integral part of the sloping cap 49, and the nut being secured down upon a main front to rear tubular trunnion 50 hereinafter more fully mentioned.

Adequate sliding and sealing surfaces between each adjacent two of the telescoping mast units are provided adjacent the tops of the respective units 31, 32, 33, 34, and 35 by bearings 53, packing gland nuts and bearings 52, stuffing boxes 54 welded to the tops of the four outer units 31, 32, 33, and 34, and wiper rings 55.

Slung from the cap 49 at the top of the inner cylinder 35 is the main rear to front horizontal tubular trunnion 50 to the exterior top surface of which is welded a cross box-like structure having side channel formations 89 to the webs of which are bolted angles 88 having lower flanges engaging the bottoms of the channel formations 89. These angles 88 and channels 89 are also bolted to the webs of vertical support channels 76 welded to the flanges of the units forming an inner frame member 63. There are four of these frame members which will be hereinafter fully described. The main longitudinal trunnion 50 is also welded to transverse short tubes 86, Figure 13, which tubes 86 are also welded to the webs of the channels 89, the tubes 86 being also bolted to the angles 88 and the channels 89.

The frame channel unit pairs are four in number, Figures 13, 14, and 15, and they have a foot plate 70 formed with side extensions 71 to which are bolted overlying front to rear horizontal plates 72 lying adjacently exteriorly of the webs of the outer stationary frame units 60 and welded thereto.

The opposed pairs of frame channel units 60, 61, 62, and 63 are respectively secured together by crosswise corrugated strengthening members 75, Figures 1, 2, 3, 13, and 15, which are welded at their ends to the outer faces of the flanges of the respective pairs of opposed units 60, 61, 62, and 63. There are a plurality of spaced sets of these corrugated strengthening members 75 throughout the height of the frame, as clearly appears in Figures 1, 2, 3, and 13.

Interposed between the webs of the respectively adjacent pairs of telescoping frame units 60, 61, 62, and 63, and secured to the webs of the inner unit of each pair of units, at the top of the frame, are wear plates 81, Figures 13 and 15. There are like wear plates 80 at the bottom of the frame secured to the inner frame unit of the respectively adjacent pairs of frame units, Figure 14.

Corresponding wear plates 84, at the top of the frame, and wear plates 83 at the bottom of the frame, are interposed between the flanges of the respectively adjacent pairs of telescoping frame units and secured to the flanges of the inner units of the respective pairs.

External stop plates 82, at the bottom of the frame, are secured by welds 91 to the webs of the inner units of the respectively adjacent pairs of telescoping frame units 60, 61, 62, and 63; and, adjacent the top of the frame, there are interposed internal stop plates 85 secured by welds

92 to the webs of the outer of the respectively adjacent pairs of frame units.

The function and operation of the stop plates 82 and 85 will be hereinafter fully described.

Operation of the mast and frame

Preliminary steps and operations initially essential to place the apparatus in condition for elevating the mast 4 and the frame 5 will be hereinafter fully described. Assuming these necessary initial steps have been taken, the hydraulically-operated tower is raised and lowered as follows:

By means and in a manner hereinafter fully described, oil is caused to flow through the port 20 in the base plate 36 of the mast 4, Figure 14, and the oil pressure effects the upward movement of the inner four mast cylinders 32, 33, 34, and 35 which, Figures 13 and 14, carry the inner frame unit 63 upwardly with them. When the upper external ring 44 on the mast unit 32 engages the bottom of the stuffing box 54 welded to the outer fixed mast unit 31, the upward movement of the mast unit 32 ceases. Thus, the mast member 32 then becomes stationary but the mast units 33, 34, and 35 continue moving upwardly. At this time the lower stop plate 82 secured to the inner frame unit 63 is below the upper stop plate 85 secured to the frame unit 62. When the lower stop plate 82 secured to the inner frame unit 63 engages the upper stop plate 85 secured to the frame unit 62, the frame unit 63 carries the frame unit 62 upwardly with it. The upward movement of the mast members 33, 34, and 35 carrying with them the frame members 62 and 63 continues until the upper stop ring 44 secured externally of the mast unit 33 engages the stuffing box 54 of the now stationary mast unit 32, at which time the upward movement of the mast unit 33 is stopped. At this time the lower stop plate 82 on the frame unit 62 is below the upper stop plate 85 on the frame unit 61. Thus, the mast units 31, 32, and 33 will now be stationary, and the mast units 34 and 35 will continue upwardly carrying with them the frame units 61 and 62. When the lower stop plate 82 on the frame unit 62 engages the upper stop plate 85 on the frame unit 61, the latter unit is carried upwardly with the units 62 and 63.

When the upper stop ring 44 secured externally to the mast unit 34 engages the stuffing box 54 welded to the mast unit 33, the upward movement of the mast member 34 is stopped and, thereafter, only the inner mast unit 35 continues upwardly carrying with it the frame units 61, 62, and 63. This upward movement of the inner mast unit 35 and frame units 61, 62, and 63 continues until the upper stop ring 44 secured externally of the mast unit 35 engages the stuffing box 54 welded to the mast unit 34. At this time the lower stop plate 82 secured to the frame member 61 is adjacently below the upper stop plate 85 secured to the fixed frame member 60.

When it is desired to lower the mast 4 and the frame 5, by means hereinafter fully described, oil flows from the interior of the mast through the port 20 and the lowering of the inner mast unit 35 commences and carries the inner frame unit 63 with it. The lowering of the mast unit 35 as a single member continues until the external stop ring 42 secured adjacently the lower end thereof encounters the internal stop ring 41 secured to and adjacent the bottom of the mast unit 34. Also, the lowering of the frame unit 63 continues until the bottom stop plate 82 secured externally thereof engages the upper stop plate 85 secured internally of the frame member 62, after which both the frame members 62 and 63 descend together. This sequence of operations is repeated, the external stop rings 42 and the cooperating internal stop rings 41 successively picking up additional mast units, and the lower stop plates 82 and the upper stop plates 85 successively picking up frame units, until the four inner mast units 32, 33, 34, and 35 settle together upon the base 36, and the three internal frame units 61, 62, and 63 settle together upon the base 70, Figures 13 and 14.

As hereinafter fully explained, it is not necessary that the upward extension of the tower mast and frame units be a maximum, such as has been described, but the upward extension may be stopped at any point either mechanically or by opening a switch A, Figure 23, which will be hereinafter fully described.

Claims to the extensible mast structure described and shown in the instant application are presented in a divisional application, Serial No. 508,486, filed May 16, 10 1955.

Structure of the fixed and transversely-movable platforms, and operation of the transversely-movable platform

The working floor 74 of the transversely-movable platform 7 and the fixed platform 6 are mounted upon front and rear transverse channels 135, Figures 6 and 22, and longitudinal channels 153. The channels 135 and 153, the platform 74, and the upper front and rear cross beams 136 and longitudinal beams 136¹ of the platform are secured together by bolts 137. This platform structure is provided with a knockdown railing structure 73, Figures 3, 17, 21, and 22, and, when it is used as a movable structure, is transversely movable upon a fixed base 145 to the position shown in Figure 3. The stationary platform 6 is mounted upon a base 15, Figure 1. Both the bases 15 and 145 are mounted upon the top of the extensible tower units. The stationary platform 6 is insulated from the tower top by a 4-point support.

Referring to Figures 4 and 5, it will be noted that in 30 making its maximum transverse movement the platform 7 moves from the dot-and-dash line position shown therefor in Figure 4 to the full line position shown therefor in Figure 5. This movement of the platform 7 is effected by various instrumentalities hereinafter fully described. The 35 platform 7 includes a fixed frame having a left side channel member 113 and a right side channel member 106, Figure 4, connected by certain of the operating instrumentalities which are fixed members telescoping with and otherwise cooperating with other instrumentalities which 40 are movable members, including a main front to rear channel 100, Figure 5, which movable instrumentalities effect a movement of the platform 7 through a distance about twice the extent of the distance through which the channel member 100 moves. In other words, the channel 45 100, when the platform 7 is in its closed position, is disposed adjacently within the right hand frame member 106 and, when the platform 7 is in its fully extended position, the channel member 100 has moved to the dotted line position shown therefor in Figure 5; whereas, the left 50 hand edge 111 of the platform 7 depending from a frame member 153 has moved from the position shown therefor in Figure 4 to the position shown therefor in Figure 5, and the right hand member 114 of the platform 7 has moved from the position shown therefor in Figure 4 to the 55 position shown therefor in Figure 5. The channel 114 at the right hand end of the platform 7 is provided with tubular insulation liners 65, Figures 5 and 7, which will hereinafter be described more fully.

The aforementioned instrumentalities for moving the 60 platform 7 include two series of three transverse telescoping mounting tubes, Figures 4, 5, 6, 7, 10, and 13, of which the intermediate tube of each series is designated 102, the interior, 103, and the exterior, 104. The exterior tube 103 is welded at its left end to the left end 65 channel 113 of the fixed frame, Figure 7, and at its right end to the right end channel 106 of the frame, the intermediate mounting tube 102 telescoping within the tube 103, Figure 7, and being secured at its right end to the main longitudinal channel 100, Figures 4, 5, 7, and 10, and the inner mounting tube 104 telescoping within the intermediate tube 102 and being secured at its right end to the right end platform channel 114. The tubes 102, 103, and 104 intersect the front to rear tubular trunnion 50, Figure 7, and the outer tube 103 is welded thereto. 70 Each of the tubes 102, 103, and 104 is substantially

equal in length to the transverse dimension of the platform 7 and when fully extended the combined length of the tubes is substantially equal to the distance P—P, Figure 3. The distance through which the main longitudinal channel 100 has moved in effecting full movement of the platform 7 is indicated by line R—R, Figure 3. Secured to the exterior surfaces of the movable tubes 102 and 104, and adjacent each end thereof, are bushings 119 and 118, respectively, which are held by end rings 151 and 150, respectively, Figure 7.

Another instrumentality involved during the moving of the platform 7 is a hydraulic cylinder 154, Figures 4, 6, 8, and 10, having oil ports 153 and 159 at its respective ends, the cylinder 154 intersecting the front to rear trunnion 50 and being fixed relative thereto by plates 160 and 162 welded to the cylinder 154 and abutting the two sides of the trunnion 50. The right end of the cylinder 154 is secured to the right fixed frame channel 106. A piston 155 slides in the cylinder 154 and the right hand end of its stem 156 is secured to the aforementioned front to rear main channel 100.

The hydraulic cylinder 154 is disposed forwardly of the rear set of telescoping mounting tubes 102—103—104, Figure 6, and although secured by plates 160 and 162, as hereinbefore mentioned, is not fastened transversely of rear trunnion 50. Fluid tight bearing elements 157 for the cylinder stem 156 are secured to the right hand end of the cylinder 154 and the right end fixed frame channel 106.

Another instrumentality for moving the platform 7 comprises two pairs of telescoping tracks, Figures 4, 5, 6, and 9, of which the outer track 121 of each pair is welded at its left end to an end of the left side fixed front-to-rear frame channel 113, and at its right end to an end of the right side fixed front-to-rear frame channel 106, Figure 9. An inner track 120 telescopes within the outer track 121 and is welded at its right hand end to one end of main front-to-rear frame member 100. Rollers 125, Figures 9 and 10, travel on the tracks 120 and 121, these rollers 125 being secured to and suspended from the working floor 74 in a manner hereinafter fully described. At its left end the inner track 120 is formed with a pair of spaced extension plates 122, Figures 6 and 9, between which is mounted a follower wheel 123.

The elements for suspending the rollers 125 from the working surface portion 74 of the transversely-movable platform 7 comprise angular roller brackets 126, Figure 10, having welded thereto trunnion members 127 within which are rotatably mounted the spindles 128 of the rollers 125, the roller brackets 126 depending from insulation covers 129 to which they are secured by bolts 132, the insulation covers 129 lying beneath and being bolted to the platform 74 by bolts 130, layers of insulation 131 being interposed between the bottom surface of the working floor 74 and the top surfaces of the insulating covers 129.

Another instrumentality for moving the platform 7 includes a pair of transversely-spaced movable horizontal sheaves 109 and 109¹, Figures 4, 5, 6, 10, 11, and 12, of which the left hand sheave is designated as 109 and the right hand sheave 109¹. These sheaves 109 and 109¹ are mounted so as to be carried by a movable transverse dish-shaped member 108 which slides in a transverse fixed flanged dish-shaped member 124, Figures 4, 6, 7, and 12, welded at its left end to and upon channel 110 which in turn is mounted on fixed frame channel 113, Figure 7, the member 124 being welded at its right end to the top of a plate 107¹ which is mounted upon and welded at its lower end to fixed frame channel member 106. The right end of the dish-shaped sliding member 108 is secured to a depending angular plate 107, Figures 7 and 10, which at its lower end is secured by set screws 101 to the main front-to-rear channel 100, Figure 7. This movable dish-shaped member 108 is mounted on opposed triangular plates 112 to which it is welded, the

plates 112 being welded to the angle 107 and bolted to the movable dish-shaped plate 108.

The spindles 116 and 116¹ of the respective sheaves 109 and 109¹ are welded to the movable dish-shaped plate 108, Figures 10 and 11, these sheaves turning upon bushings 117 which are held in position by horizontal angular plates 115, Figures 10 and 11, welded by downwardly inclined left end portions to the top of the movable dish-shaped plate 108. The upper right ends of the angular plates 115 extend adjacently beneath the heads of the spindles 116 and 116¹ and rest upon and terminate slightly beyond the bushings 117 of the sheaves 109 and 109¹, Figure 11.

A cable 90 traverses the sheaves 109 and 109¹, the sheaves being mounted and secured so as always to hold the cable 90 taut. The respective ends of the cable 90, Figures 4 and 12, are secured in brackets 176 and 180 which, in turn, are secured to the flange of the fixed dish-shaped plate 124 slightly to the left of the right sheave 109¹. An adjusting rod 178 to regulate the tension of the cable 90 is threaded in a side pocket of the clamp 180 and is supported at its outer end by a bracket 177 secured to the fixed flanged dish-shaped plate 124. The clamp 180 is formed with two adjacent pockets, into one of which the adjusting rod 178 extends and in the other of which one end of the cable 90 is secured. The flanged sides of the fixed dish-shaped plate 124 rest on the flanges of the movable plate 108 which, in turn, rest on spacers 174, Figure 6.

Referring particularly to Figure 10, an insulation pad 167 is secured to and beneath the working floor 74 of the platform 7, as also an insulation cover 168 beneath the insulation pad 167, by bolts 166. Suspended from the platform 74 by bolts 170 which pass through the insulation cover 168 and the pad 167 is an angle 165 to the depending leg of which is secured by bolts 181 a cable clamp 175, Figure 10. The cable 90 is tightly clamped by the member 175 adjacently to the right of the left hand sheave 109.

It is evident from the description just preceding, and by reference to the showing in Figures 4, 5, 6, 10, 11, and 12, that any movement to the right of the main front-to-rear channel 100 will move the sheaves 109 and 109¹ accordingly and that the platform 7 will be pulled by the cable 90. It is also evident that the ends of the cable cannot move. Therefore, the platform 7 will be pulled by the cable 90 at approximately twice the speed of the movement to the right of the sheave supporting dish-shaped plate 108. If the sheave members make a complete movement, the sheaves 109 and 109¹ will have assumed the position shown in full lines for the sheave 109 in Figure 4 and indicated for the sheave 109¹ in Figure 5. The platform 7 will have been moved approximately twice the distance and be in a position indicated therefor in full lines in Figure 5.

During this full movement of the platform 7, the portion of the cable 90 clamped by the member 175, Figure 10, will have moved to the right, relatively to the frame channel 100 and the sheaves 109 and 109¹, a distance substantially equal to the distance between the sheaves 109 and 109¹. This effects a platform movement of this distance in addition to the distance which the channel 100 and the sheaves 109 and 109¹ themselves have moved. Thus the total movement of the platform 7 is substantially twice that of the movement of the movable frame and the sheaves 109 and 109¹.

The action whereby the mast 4 and the frame 5 are vertically extended and lowered, and the platform 7 is transversely moved, is hydraulic, and the path of oil for effecting this action is particularly shown in Figures 8, 14, 15, 16, and 23. This oil path comprises an outlet 18 from the bottom of the tank 10 through a sediment bulb casing 19, thence to the pump 11, thence to a control valve E, thence to a metering valve F, and thence through loop 372 to the interior of the mast 4 through the inlet

20. The return of the oil is from the mast 4 through the metering valve F by way of the loop 372 and thence to the control valve E and back to the tank inlet 24. This oil flow effects the raising and lowering of the mast 4 and the frame 5 and is obtained by the use of some other detail structure which will be fully described hereinafter. No actual oil pressure is required, however, to lower the mast 4 and the frame 5, these structures coming downwardly by their own weight when the path or flow of oil is properly set, as hereinafter fully described.

The oil for moving the platform 7 outwardly flows through the control valve E from the tank 10 and thence to the port 158 of the hydraulic cylinder 154 forcing oil from the port 159 whence it flows back to the tank 10 through the control valve E. The oil for retrieving the platform 7 flows reversely to that just described in passing between the control valve E and the hydraulic cylinder 154. Other detail of this oil flow for moving the platform 7 will also be hereinafter fully described.

The metering valve F, Figures 15, 16, and 23, is located between the control valve E and the mast 4 and frame 5 and determines the flow of oil according to the height of the frame 5. This metering valve F has a casing 232 formed with ports 233 and 234 with which an oil line 230 from and to the oil control valve E, and an oil line 231 to and from the mast 4, respectively communicate. Within the casing 232 is a valve 235. The stem 236 of the valve 235 is engaged at its outer end by a lever 237 which is pivotally mounted intermediate its ends in a block 238 mounted on the casing 232. One end of the lever 237, on the side of the pivotal mounting where the valve stem 236 is engaged, tends to move downwardly toward the casing 232 under the influence of a spring 239 secured at its top to the outer end of the lever 237 and secured at its bottom to a bracket 305 secured to the casing 232. A stop plate 275, Figure 16, erected on the valve casing 232 determines the extreme downward movement of the lever 237 by means of a screw 245 adjustably mounted on the lever 237. The inner end of the lever 237 intersects the frame units 61, 62, and 63 and is formed with an end angle plate 237¹ through which extend adjusting screws 307 and 308 which at their head ends can abut stops 240 and 241 secured respectively to the frame units 61 and 62. When the head of the adjusting screw 307 abuts the stop 240, a maximum flow of oil into the mast 4 results. The adjusting screw is set to produce the desired maximum flow and this continues as long as only the frame unit 63 is moving upwardly. When the head of the adjusting screw 308 abuts the stop 241, then a lesser amount of oil flow results. This occurs when the frame unit 62 moves upwardly carrying the adjusting screw 308 with it. It will be understood that the tension of the spring 239 holds the inner end of the angle plate 237¹ upwardly in such position that the head of the screw 308 will abut the stop 241 if the position of the frame unit 62 so permits. The amount of movement of the adjusting screw 308 in varying the oil flow from the maximum to the intermediate flow is indicated by the distance by which the head of the screw 308, Figure 16, is spaced from the stop 241. It will be understood that when the head of either of the screws 307 or 308 is abutting its stop 240 or 241 to control oil flow, the frame member upon which the controlling screw is mounted is not then moving upwardly so that the abutting position of the head of the screw against its stop determines the oil flow and preserves it constant until the frame member has moved upwardly and the next amount of oil flow commences to function. The adjusting screw 245 is so set that the minimum flow of oil results when the screw 245 contacts the stop plate 275. This minimum flow of oil is effective when all of the frame units 61, 62, and 63 are moving upwardly and are carrying with them the adjusting screws 307 and 308.

Secured to and adjacent the top of the stationary frame member 60 is a cutout switch 243. This switch functions

when the adjacent frame unit 61 has reached its maximum height by reason of a contact 244 secured exteriorly of and adjacent the bottom end of this adjacent frame member 61, an engagement of the contact 244 with the cutout switch 243 cutting off the flow of oil into the mast 4 by electrical control, thus stopping the whole operation.

Electric control and hydraulic operations

Referring to the diagrammatic showing in Figure 23, 10 an oil line 225¹ leads from the outlet 18 of the tank 10 to an inlet port 302 of a relief unit W of the oil control valve E. An oil line 315 leads from the outlet 317 of a gathering unit L of the control valve E to the inlet 24 of the oil tank 10. An oil line 318 leads from a relief valve G in the valve relief unit W and communicates with the oil line 315. An oil line 230 communicates at its respective ends with a port 366 from the mast control unit T of the control valve E and a port 233 in the casing 232 of the metering valve F. An oil line 231 communicates with a port 234 in the casing 232 of the metering valve F and a port 20 in the mast 4 communicating with the interior of the mast below the mast units. An oil line 314 communicates with a port 329 in the platform unit X of the control valve E and a port 158 in the left end of the hydraulic cylinder 154. An oil line 251 communicates with a port 159 in the right end of the hydraulic cylinder 154 and with a port 375 in the platform control unit X of the control valve E and a port 159 in the right end of the hydraulic cylinder 154. Preferably, both of the oil lines 251 and 314 are formed of flexible tubing.

A general number for the electric controls is 12, and reference is now made to Figure 23 wherein such control is shown. There are four switches A, B, C, and D in the electrical system for controlling the up and down movements of the mast 4 and the outward and inward movements of the transversely-movable platform 7, one of these switches, A, being in the main conductor line 300 leading from the truck battery to the cutout switch 243, and the other three switches B, C, and D being in respective branch lines, switch B being in a branch line 322 leading to the lower of a double solenoid assembly A²—B² in which the two solenoids A² and B² are in opposed spaced relation, each having valve bodies within and through which play the respective stems A' and B' of armature cores, the extended ends of the stems A' and B' being encircled by suitable windings adapted to be energized by the closing of the respective switches A and B. The switch C is in a line 369 having a winding portion thereof encircling the outwardly-extended portions of the stem C' of the armature core of the upper unit of a double solenoid assembly C²—D², and switch D being in a line 367 leading to the bottom solenoid unit of such double solenoid assembly C²—D². There are also suction cylinders 254 and 255 within which slide pistons 276 and 280 having depending stems 257² and 301, respectively, which extend into the oil control valve E. For a purpose hereinafter fully described, the stem of the piston 276 which extends into the oil control valve E is subdivided into two portions 257² and 257'. Likewise, the stem of the piston 280 is subdivided into two portions 301 and 301'. The adjacent ends of these two respective stem portions are secured together by a clevis 193, Figure 34, pivotally mounted on an emergency lever 191 by a pin 193', the inner end of the lever 191 being pivotally mounted by a pin 192' in a boss 192 welded to the channel 26 which is secured to the control housing 13. There is an assembly such as shown in Figure 34 for each of the vacuum cylinders 254 and 255 and their purpose is to provide means for manually actuating the mast 4 and/or the transversely-movable platform 7 if, for any reason, there is any engine or other trouble preventing the proper operation of the vacuum cylinders 254 and 255 and the oil flow control valve E.

All of the plungers secured to the respective stems of the solenoid armature cores within the valve bodies

formed by the respective solenoids are normally in their innermost positions. Plunger A' plays in a conductor 368 leading from the cutout switch 243 and plunger C' plays in conductor 369 leading from switch C. The stem B' of the solenoid B² plays in a conductor 322 leading from the switch B and the stem D' of the solenoid D² plays in a conductor 367 leading from the switch D. Vacuum lines 252 and 252' extend to and from a vacuum pump 253 and have branches 381 and 382 which respectively communicate with the top of the chamber of the solenoid B², and with the top of the chamber of the solenoid D². There is also vacuum line 366 communicating with a port formed in the inner end of the bottom of the chamber of the solenoid A² and with a port formed in the inner end of the valve body of the solenoid C². There are also branch vacuum lines 281 communicating with ports formed in the inner end of the respective chambers of the solenoids B² and D² and with ports formed in the inner end of the respective chambers of the solenoids A² and C². There are also vacuum lines 298 and 299 communicating, respectively, with the centers of the valve bodies of the solenoids A² and C² and the upper part of the respective vacuum cylinders 254 and 255. Also, vacuum lines 298' and 299' connect the bottoms of the respective vacuum cylinders 254 and 255 with the centers of the respective chambers of the solenoids B² and D². There are relief ports 311 through the outer parts of the valve bodies of the solenoids A² and C², and relief ports 312 through the outer ends of the valve bodies of the solenoids B² and D².

It is apparent from Figure 23 that the relief ports 311 are open from the valve bodies of solenoids A² and C² when the plungers of the respective stems A' and C' thereof are in their inner positions and that the relief ports 312 are open from the valve bodies of the solenoids B² and D² when the plungers of the respective stems B' and D' thereof are in their inner positions.

The oil flow control valve E is shown in cross-section in Figure 23, and details of two movable intermediate units T and X thereof are shown in Figures 35, 36, 37, and 38, Figure 35 being the position of the spool in unit T when the mast is being raised; Figure 36 being the arrangement of the spool in unit T when the mast is being lowered; Figure 37 being an arrangement of the spool in unit X when the platform 7 is being moved outwardly; and Figure 38 being the arrangement of the spool of unit X when the platform 7 is being retrieved. Of the other units of the relief valve E, unit W operates as an oil relief unit, and unit L acts as a gathering or exit unit through and from which oil is returned to the tank 10 through the inlet port 24. Units W and L are stationary.

The units of the control valve E are formed with ports and passage, and the unit T and X thereof with spools having reduced portions communicating with the ports and passages in certain positions of the spools for operation of the mast structure and for operation of the transversely-movable platform 7, Figure 3, these spools T and X being secured to the respective stem portions 257' and 301' of the pistons for the vacuum cylinders 254 and 255. The structure and operation of these various auxiliaries of the control valve E will be hereinafter fully described.

The mast units 32, 33, 34, and 35 are started on their upward travel by the closing of the switch A, Figure 23. Such closing of the switch A energizes the winding encircling the stem A' of the solenoid A² and lifts the plunger within the solenoid A² and through the vacuum line 281 subjects the inner end of the valve body of the solenoid A² to vacuum. By the vacuum line 298 the top of the cylinder 254 is subjected to vacuum thus causing the piston 276 of the cylinder 254 to rise. This effects an upward movement of the stem 257'—257' of the piston 276, causing a movement of the spool of the control valve unit T, the effect of which is to start an upward

movement of the mast cylinders 32, 33, 34, and 35, which will be hereinafter fully explained.

Likewise, the starting of the downward movement of these mast cylinders is effected by closing the switch B which through the outward movement of the stem B' and piston of the solenoid B² opens the top of the chamber of the solenoid B² to vacuum, which vacuum is communicated to the cylinder 254 by the branch line 298' below the piston 276 thereof, causing the stem 257'—257' to move inwardly. This starts a downward movement of the mast cylinder 35.

To control the movements of the piston 155 of the hydraulic cylinder 154, Figure 23, the action of the piston 280 of the vacuum cylinder 255 by reason of the movements of the stems C' and D' and their pistons of the solenoids C² and D² is the same as that just described with reference to the piston 276 of the vacuum cylinder 254, the conductor 369 from the switch C energizing the winding of the solenoid C² and the conductor 367 from the switch D energizing the winding of the solenoid D². These actions result respectively in the inward and outward movements of the stem portions 301 and 301' of the piston 280 to effect flow of oil to and from the hydraulic cylinder 154 which through its piston rod 156 effects the movements of the main platform frame member 100 of the transversely-movable platform 7 to move the latter outwardly and inwardly.

A regulator H, Figure 23, is provided for the movements of the valve stems 257' and 301. This regulator is connected to the throttle of the engine carburetor by a wire 262. The regulator H accelerates in both directions. The regulator H includes a plate 245 positioned slightly above the blocks 246 and 247 secured to the respective vacuum cylinder stems 257' and 301. The plate 245 is moved upwardly through the medium of the blocks 246 and 247 whenever the vacuum cylinder stems 257' and 301 move upwardly. Such upper position of the plate 245 is indicated by dot-and-dash lines in Figure 23. A spring 248 is secured at one end to the plate 245 and at its other end to a spacer block 250 secured to a stem 197 to whose outer end is secured a carburetor wire 262. A second spacer block 188 is secured to the stem 197 adjacently below the plate 245. Secured to the stem 301 below the block 247 is a block 263¹ whose under surface is engaged by a lever 313 pivoted intermediate its ends and also engaging the under surface of a block 277 secured to the stem 197 above the spacer block 250. The operation of these several elements of the regulator H will be hereinafter fully described.

As stated, the control valve E comprises three units W, T, and X for raising and lowering the mast 4 and frame 5, and an additional unit X, if the platform 7 is utilized and if it is desired to move this platform 7 transversely of the truck body 21.

This control valve E is shown in Figures 23, and 35 to 38, inclusive. Figure 23 shows a horizontal section of the control valve E, having the four units W, T, X, and L, with the oil flow control parts, which are in the sections T and X, in neutral position. Figure 35 is a vertical section of the unit T for controlling the oil flow to and from the mast 4 with its control parts in position to permit oil flow to the mast 4. Figure 36 is a vertical section of the unit T with its control parts in position to permit oil flow back from the mast 4. Figure 37 is a vertical section of the unit X for controlling oil flow to and from the hydraulic cylinder 154 of the transversely-movable platform 7, with its control parts in position to permit oil flow which effects an outward movement of the transversely-movable platform 7. Figure 38 is a section of the unit X, similar to Figure 37, but in which the control parts are in position to permit retrieving of the outwardly-projecting transversely-movable platform 7.

The control valve units W, T, X, and L are formed with side passages which, in certain positions of the

control parts of the units T and X, provide free oil flow throughout the length of the valve E. The passages thus formed are designated 322 and 380. Furthermore, the units T, X, and L and the units W, T, and X are formed with passages which, in certain positions of control parts of the units T and X, provide free flow through these two respective sets of units. The passages thus formed are 304 and 379. Also, there are end cross passages one of which is passage 303 in the unit W which communicates with the passage 322, the passage 304, and an overflow valve G which communicates with one end of the passage 380. The other end passage 309 is formed in the gathering unit L and communicates at its ends with the passages 322 and 380 and also the intermediate passage 379. A port 302 in the unit W communicates with the oil line 225¹ leading from the tank outlet port 18. A port 317 in the valve unit L communicates with the oil line 315 leading to the tank inlet 24. Communicating with the oil line 230 leading to and from the metering valve F is a port 306 formed in the mast control unit T. Communicating with the oil line 314 leading to the port 158 of the hydraulic cylinder 154 is a port 320 formed in the platform control unit X. Also, formed in the platform control unit X is a port 375 which communicates with the oil line 251 connected by the port 159 to the hydraulic cylinder 154. The ports 306, 320, and 375 are formed in units T and X which are movable, as hereinafter fully described, so that the oil lines 230, 251, and 314 will be comprised of flexible tubing in whole or in part. Furthermore, the lines 251 and 314 communicate with a hydraulic cylinder 154 which moves upwardly and downwardly on the platform 7 as the latter is lifted and lowered by the upward and downward movement of the mast 4 and the frame 5.

The control parts within the mast control unit T of the control valve E include a spool K secured to the stem portion 257¹ of the piston 276 of the vacuum cylinder 254, this spool K sliding transversely of the control unit T and having parts V, M, and J of reduced cross section whereby oil flow can be permitted through the longitudinal passages 322, 379, and 304. Likewise, a control part for the unit X includes a spool N secured to the stem 301¹ of the piston 280 of the vacuum cylinder 255, this spool N having parts O, S, and Q of reduced cross section which also control oil flow through the lengthwise passages 322, 379, and 304.

Oil for moving the tower upwardly or for moving the transverse platform 7 outwardly or inwardly enters the control valve unit W from the line 225¹ through the port 302. Oil for moving the tower downwardly enters the port 306 in the control valve unit T from the oil line 230. While the platform 7 is being moved outwardly, the return oil forced from the hydraulic cylinder 154 enters the control valve unit X through the port 375. While the platform 7 is being retrieved or returned to its normal inner position, the oil forced from the cylinder 154 enters the control valve unit X through the port 320.

The positions of the valve units T and X for these several operations and the respective paths of the oil are as follows:

When the spool K is pulled to the position shown in Figure 35, oil enters from the line 225¹ through the port 302 of the valve unit W and thence flows by passages 303 and 304 through the unit W and thence passes the reduced section J of the unit T and passes outwardly through port 306 into the line 230 which leads through the metering valve F into the bottom of the mast 4. This effects the upward movement of the mast 4 and the frame 5.

When the spool K is in the position shown in Figure 36, oil from the mast 4 flows into line 230 and passes through the port 306 in the valve unit T and thence passes the reduced section M of the spool K into the passage 379 by which it passes the reduced section Q of

the unit X and thence through the gathering unit L and outwardly of the port 317 into the line 315 leading to the oil tank inlet 24. Such movement of the oil effects the lowering of the mast 4 and the frame 5.

When the spool N of the valve control unit X is in the position shown in Figure 37, oil from the line 225¹ passes into the valve unit W through the port 302 and thence by passage 303 and 304 flows around reduced section J of valve unit T and passes reduced section Q of valve unit X whence it flows through port 320 in valve unit X into oil line 314 and through the port 158 into the left end of the hydraulic cylinder 154. At the same time the oil being forced out of the hydraulic cylinder 154 through the port 159 flows via the oil line 251 and thence through a port 375 in the valve unit X whence it flows by the stem 319 of the spool N into the passage 380 and thence by passage 309 and port 317 into the oil line 315 leading to the tank inlet port 24. This effects the outward movement of the transversely-movable platform 7.

When the spool N of the valve unit X is in the position shown in Figure 38, the oil being forced from the hydraulic cylinder 154 through the port 158, as herein-after described, moves via the oil line 314 through the port 320 in the valve unit X and thence passes around the reduced section S of the spool N and into passage 379 whence it passes through port 317 of the gathering unit L into the oil line 315 leading to the inlet port 24 of the tank 10. The oil for effecting the movement of the piston 155 of the hydraulic cylinder 154 toward the left for the procedure just described is derived from the oil line 225¹ and passes through the port 302 of the control valve unit W and thence by passages 303 and 304 passes the reduced section J of the spool K and thence by the reduced section Q of the spool N passes through port 375 to the oil line 251 whence it flows through the port 159 into the right hand end of the hydraulic cylinder 154. Thus, a retrieving or inward movement of the transversely-movable platform 7 is effected.

It will be understood that only one of the valve control units T and X is out of neutral position, Figure 23, at any one time and this only, when the tower is being raised or lowered or the transversely-movable platform is being moved outwardly or retracted.

Any excess of oil pumped greater than is required for operating purposes flows by the relief valve G, Figure 23, into the oil line 318 which communicates with the oil line 315 leading to the tank inlet 24. When the units T and X of the control valve E are both in neutral position and the pump 11 is operating, the oil flows from line 225¹ through port 302, passage 303, passage 322, passage 309, and port 317 to oil line 316 and thence to tank inlet 24. This flow of oil through the passage 322 is effected only when both of the spools K and N are in neutral position, inasmuch as this passage 322 is blocked off when either of the spools K or N is in operative position.

The stems 310 and 319 of the spools K and N, respectively, are provided with discs 360 and 361 upon which discs the ends of compression springs 271 and 272, respectively, bear, these discs being disposed adjacent the inner ends of recesses 362 formed in the end portions of the spools T and X and shoulders 364 formed in housings 363 secured to the ends of the respective units T and X. The stems 310 and 319 intersect the discs 360 and 361 and can move outwardly thereof when the spools K and N are moved to the left, as shown in Figures 36 and 38, the outer discs 361 being stopped by the abutment shoulders 364. Collars 365 and 366 welded to the outer ends of the respective stems 310 and 319 prevent the inward movement of these stems relatively to the outer discs 361. When the spools K and N are moved to the right, as shown in Figures 35 and 37, the springs 271 and 272 are compressed. The springs 271 and 272,

the discs 361, and the shoulders 364 thus provide balance or equalization for the control of the stems 257² and 301 of vacuum cylinder plungers 276 and 280, Figure 23.

Referring particularly to the regulator H, Figure 23, this mechanism is an automatic engine speed control and the action is initiated by the vacuum. It should be understood that a lowering of the mast 4 does not require a throttle operation inasmuch as the mast comes down by its own weight. Therefore, referring to the action of the regulator H, insofar as the vacuum is required for lifting the mast 4 and for moving the transverse platform both outwardly and inwardly, the plate 245 of the regulator always moves upwardly, an upward position therefore being indicated by dot-and-dash lines in Figure 23, and the purpose of the spring 248 is only to return the regulating mechanism to its original or normal position shown in Figure 23. The pull of the spring 248 is regulated by the distance between the spacer blocks 188 and 250 secured to the stem 197.

The upward movement of the stem 257² incident to the upward movement of the mast 4 causes the block 246 to lift the plate 245 against the tension of the spring 248. The downward movement of the stem 257² acts to adjust the control of the ports and passages of the control valve E so that the oil can flow out of the bottom of the mast 4. The upward movement of the stem 301 incident to the outward movement of the transverse platform 7 lifts the plate 245, and the downward movement of the stem 301 incident to the retrieving of the platform 7 acts through the pivoted lever 278 also to lift the plate 245. Therefore, the regulator H accelerates in both directions and the plate 245 always moves upwardly for the regulating action.

Claims to the control system shown and described in the instant application are presented in a pending divisional application, Serial No. 508,485, filed May 16, 1955.

Platform railings

All the platforms are provided with railings which can be raised when the tower is used, and which can be collapsed to lie on the platform working floors with front and/or front and rear end portions of the railings extending longitudinally from the working floor when the tower is not being used. The railing 95 for the rotary platform 8 is a unitary formation and can be raised and collapsed as such unitary formation. This railing 95 comprises a plurality of relatively pivoted railing parts including posts and bars forming a fence-like structure bounding the working area of the platform 8, as herein-after fully described. The railing 73 for the stationary and transversely-movable platforms 6 and 7, respectively, are comprised of two similar half-formations, and each half thereof is raised and collapsed as a unitary formation.

The railing for the stationary platform 6 is designated by the general number 48, Figures 1 and 2; the railing for the transversely-movable platform 7 by the general number 73, Figures 3, and 17 to 22, inclusive; and the railing for the rotary platform 8 by the general number 95, Figures 24 to 33, inclusive. The railings utilized for the stationary platform 6 and the transversely-movable platform 7 are the same structure and are raised and collapsed in the same way. The railing 95 for the rotary platform 8 is of different structural formation and is raised and collapsed in a different manner.

The railing 48 for the stationary platform 6, Figures 1 and 2, and the railing 73 for the transversely-movable platform 7, Figures 3, and 17 to 22, inclusive, are provided with a working platform 74 which is mounted upon the transverse channels 135 and the longitudinal channels 153 and secured theretobeneath the transverse frame members 136 and the longitudinal frame members 136¹. The railings 48 and 73 include top cross end members 143 and intermediate end cross members 146, gate-like

longitudinal side members 183 hinged to the cross members 143 and 146, and front corner posts 133 and rear corner posts 134 adjacently within and to which the aforementioned railing members are secured. As clearly seen in Figure 3, an intermediate post 169 is provided for each of the front and rear cross dimensions of the railing 73. One gate-like structure 183 is hinged at one end to one side of the railing front and the other gate-like structure 183 is hinged to the opposite side of the railing rear. The gate-like structure actually comprises parallel upper and lower longitudinal rails and vertical end rails 184, and diagonal reinforcing members 198 secured to the top and bottom of the respective upper and lower longitudinal members 183. A side elevation of one of the gate-like structures is shown in Figure 17. These gate-like structures 183 are secured by hinges 185 to the top and intermediate transverse cross members 143 and 146 and to the posts 133 and 134, respectively, interiorly of the latter by bolts 187, Figure 20.

Secured to the top of the cross frame members 136, Figure 22, by the bolts 138, are the top ends of depending angular steel plates 139 which extend downwardly along the inside faces of the posts 133, 134, and 169 and thence pass outwardly under said posts and are formed with upwardly extending end portions abutting the exterior faces of the posts and having externally bent terminal portions. Thus, the bottom portions of the plates 139 form sockets in which the bottom ends of the posts 133, 134, and 169 seat. Secured by their webs to the outside faces of the respective posts 133, 134, and 169 are elongated channel-like steel members 140, Figure 21, against the side edges of the lower portion of which abut plates 172 which extend inwardly adjacent the sides of the posts 133, 134, and 169 and are secured at their inner ends to the angular steel plates 139. These plates 172 extend downwardly to a point adjacently below the upper out-turned ends of the plates 139. Welded by their angular ends to the sides of the plates 172 are horizontal U-shaped rods 141, the bodies of which pass across the members 140 as clearly appears in Figures 21 and 22.

Adjacent the top and intermediate portions of the railing, and in the two diagonally opposite corners thereof, and relatively diagonally positioned adjacent the swinging ends of the gate-like members 183, are angle plates 189 which are pivotally secured, Figure 19, to the upper and intermediate transverse cross rails 143 and 146, respectively, adjacent the upper and lower ends of the gate-like members 183. These plates 189 are mounted on pivot pins 182 adjacent an upper corner of the plates 189 so that the latter can swing upwardly of the railing as shown in dot-and-dash line in Figure 19. Secured by bolts 190 to the rails 143 and 146 are plates 195 formed at their bottom edges into trough-like formations 195¹, Figures 18 and 19, providing recesses in which latches 194 secured to the rails 183 of the gate-like structures may engage by the swinging movements on the hinges 185 of the gates 183. Furthermore, latching edges of the members 189 are of a notched formation clearly shown in Figures 18 and 19 having not only the bottom edge portion 189¹ at one end of the bottom but also an upraised opposite end bottom edge portion 189² whereby, as the latch 194 is closed its bottom edge portion 189¹ wedges the nose 194¹ of the latch 194 tightly in the trough-like formation 195¹, and the upraised bottom end portion 189² of the plate 189 forces the latch 194 tightly against the lip of the trough-like formation 195¹.

When the railings 48 and 73 are in collapsed condition, the ends and front and rear portions thereof are designed to lie flat in superimposed condition upon the working floor 74 as indicated by the dot-and-dash showing in Figure 17. This collapsed condition of the railing is effected by folding each of the longitudinal gate-like structures 183 against the inside face of one of the transverse

sides of the railing and then folding the railing with the abutting gate-like structure down upon the working floor 74. First, the gate-like structure is released from its engagement with the front or rear of the railing by pulling the lock member 189 upwardly of the member 195, as shown in dot-and-dash lines, Figure 19, and then folding the gate by the hinges 185 into position adjacently within a railing front or rear section. The release of the latching end of the member 194 from the binding bottom edge portions 189¹ and 189² of the plate 189, and in-turned inner ends 195¹ of the trough-like bottom ends of the plate 195 permit this swinging movement of the gate structure 183.

After the two gate structures 183 have been folded against the respective cross railing structures, the respective cross railing structures are folded down with their gate members by, first, lifting the corner posts 133 and 134 and the posts 169 out of their respective sockets formed by the bottom portions of the member 139 until the bottom of the channel-like member 140 intersects the body of the hook 141. This hook 141 provides a stop limiting the upward lifting movement of the respective posts. Then the railing section with its abutting gate-like member is moved into the partly collapsed condition shown in dot-and-dash lines in Figure 17. Then the structure is moved outwardly of the working floor 74 by a sliding of the surface of the member 140 upon the bottom surface of the hook 141 until the upper end of the channel member 140 engages the hook 141, in which position the bottom of the structure being laid down will extend outwardly to the position shown in dot-and-dash lines in Figure 17. This is a position in which when the structure is completely laid down will bring the lower portion of the gate member 183 closely adjacent the front or the rear of the platform 74 so that the collapsed railing lies in the dot-and-dash position shown at the bottom of Figure 17. Thus, the entire railing 73 is laid down on the floor 74 in collapsed condition in two half portions thereof whose inner edges lie closely adjacent, with the outer edges consisting only of the posts 133, 134, and 169 and the metal parts secured thereto extended forwardly and rearwardly of the platform 74 and longitudinally of the truck body 21.

Space is provided in the ends of the platform for the raising and collapsing movements of the railing by cutting away the longitudinal frame members 136, as indicated by 142, Figure 22.

The raising of the railing 73 involves an operation just the opposite of that which has just been described for its collapsing movement. It should be particularly noted that when the gate-like structure 183 is opened, the pivotal member 189 is held upwardly to the dot-and-dash position shown therefor in Figure 19 so that the latching hook of the member 194 swings freely into the trough-like portion 195¹ of the plate 195. Then the dropping of the pivotal plate 189 effects by its bottom edge portions 189¹ and 189² a wedging of the latch of the member 194 in the trough-like portion 195¹ both at the front and on the side of the latch.

The rotary platform 8, its collapsible railing 95 and its working floor 200 are shown in Figures 24 to 33, inclusive. The rotary platform 8 is mechanically operated in a manner hereinafter fully described, so that the control switches C and D, Figure 23, and the hydraulic cylinder 154 and its related elements for actuating the transversely movable platform 7 are not required. The platform 8 rotates about a bearing 332 exteriorly of a fixed spindle 328 upwardly projected into a sub-base disposed beneath the working floor 200, Figure 30, and secured at its bottom to the inner members 63 of the telescoping frame 5. The sub-base includes a central hub 171 from which radiate spoke-like beams 329 to which are welded upwardly projected blocks 330 which depend from the floor 200, the blocks 330 being bolted to the floor 200 through insulation blocks 331. The outer ends of the beams 329

are secured to the rectangular frame formed by the channels 295, Figure 29, upon which the platform 200 is secured by bolts 297. Also secured by the bolts 297 upon the platform 200 are longitudinal frame members 296, Figures 24, 25, 26, and 29.

10 The spindle 328 is provided with an intermediate flange 333 and a bottom flange 334 welded thereto, and these flanges are welded to the frame units 63. The bearing 332 is seated at the bottom on a ring 365 mounted on a thrust washer 335 seated in the face of a ring gear 208 secured by bolts 337 to the top surface of the flange 333. Secured to the top of the spindle 328 is a grooved retaining ring 209 for the platform 8, this ring being engaged by a cable 210 secured at one end thereto and secured at its opposite end to a stabilizing reel 211, Figure 24, mounted on the rotary platform 8.

15 The sub-base and the working floor 200 are rotated by means hereinafter fully described which engage the fixed ring gear 208 and this rotation can be up to 180° in each direction whereby the platform 8 can be swung in a wide arc, for outboard operation from the working floor 200, to either side of the truck chassis upon which the tower is mounted. The cable 210 is wound on and secured to the stabilizing reel 211 which provides electric current for the control switches. The flange 333 to which the ring gear 208 is secured carries a stop (not shown) that engages another and fixed stop (not shown) at about 300° rotation.

20 The rotatable platform 8 is provided with a removable cover plate 336 secured by screws 356 to the working floor 200 and axially aligned with and above the spindle 328.

25 The platform 8 is manually mechanically rotated. This is effected by a crank assembly comprising a handle 199, Figure 25, and a crank shaft 201 mounted on and adjacently forwardly of the collapsible railing 95. The crank shaft 201 is secured by bearing clamps 202 to a horizontal top front rail 344, Figure 24, and to a horizontal lower front rail 345, and by a slotted tubular bottom end portion 203 is adapted to be clutched to a lower shaft portion 321 clamped to the bottom of horizontal rail 370, Figure 33. Secured to the lower end of shaft portion 321 is a sprocket 204 with which a chain 205 engages, the chain 205 also engaging a driven sprocket 206 secured to the shaft 206¹ of a drive shaft assembly including a drive gear 207 also secured to the shaft 206¹, the gear 207 meshing with the ring gear 208 secured to the spindle 328, Figure 30.

30 The crank shaft portions 201 and 321 are not normally engaged. Normally, when no pressure is exerted upon the shaft 201 through the operating handle 199, the handle 199 is held in an upward inoperative position, indicated by dot-and-dash lines in Figure 25, whereby the slotted tube end 203 and the shaft portion 321 are not engaged, this normal position of the shaft portion 201 being induced by a crank-lifting spring 269 which is seated at its bottom end on one of the clamps 202 and upwardly urges a collar 270 secured to the shaft portion 201, the upward movement of the shaft portion 201 being limited by a stop collar 316 secured thereto and engaging the bottom face of the clamp 202.

35 The platform 8 and its collapsible railing 95 comprise, in addition to the working floor 200 and the rotating elements, vertical rear, intermediate, and front railing posts 222, 223, and 224, respectively, longitudinal bottom channels 295, Figure 29, upon which the working floor 200 is mounted, top, intermediate and bottom longitudinal side rails 212, 291, and 296, respectively, top and lower intermediate rear cross rails 214 and 227, respectively, a series of bottom crosswise bracing bars 260, 261, 262, 263, 264, and 265, secured at their ends to the lower longitudinal rails 296, and top and lower intermediate front rails 344 and 345, respectively.

40 The railing 95 is collapsible as a unit, as can be seen in Figure 26, and for this purpose certain pivoting means

are provided which are as follows: the rail 212 and the post 222 at each rear corner are secured together by a pivot bracket 282, Figure 28, having a pivot pin 283, the rail 212 and the post 223 by a pivot bracket 350 having a pivot pin 258, the rail 212 and the post 224 by a bracket 347 having a pivot pin 259, the post 222 and the rail 291 by a bracket 351 having a pivot pin 327, the post 223 and the rail 291 by a bracket 349 having a pivot pin 256, and the rail 291 and the post 224 by a bracket 348 having a pivot pin 257.

Transverse rear, intermediate, and front pivot bars 219, 220, and 221, Figure 24, are mounted at their ends in respective bottom brackets 218, 225, and 226 which are secured to the respective upright posts 222, 223, and 224. Safety plate springs 217, Figures 25, 26 and 27, secured at one end to and beneath a rear bottom cross rail 342 are engaged at their opposite and free ends, when the railing is moved to operative upright position, by downwardly-projected bosses 339 secured to the brackets 218, 225, and 226, which brackets are mounted on and at the bottom ends of the respective posts 222, 223, and 224, the springs 217 serving to hold the whole railing 95 upright.

Two of the pivot bracket structures are shown in detail, one (282) in Figure 28, being one of the upper rear bracket structures, and one (320) in Figure 31, being one of the upper front bracket structures.

Referring particularly to Figures 24, 25, 26, and 28, the pivot bracket 282 includes a corner angle 284 secured by a bolt and nut assembly 285 to the top rear cross rail 214, the angle 284 being welded to a laterally-projecting pivot pin 283 mounted in a projecting socket 286¹ welded to a plate 286 of the bracket 282 secured by bolt and nut assemblies 287—288 to the top longitudinal frame member 212. The angle 284 is also secured to the upright rear corner post 222 by bolt and nut assemblies 325—326. Therefore, the post 222 and the top cross rail 214 are pivotally mounted relatively to the longitudinal rail 212 for collapsing of this portion of the railing, as shown in Figure 26.

Referring particularly to Figures 24, 25, and 31, the front end of the top longitudinal rail 212 is pivotally mounted relatively to the upright post 224 by a pivot pin 360 projected from the angular corner member 346 of the bracket 259 and mounted in socket 347¹ projected from a plate 347 secured to the rail 212. The corner angle 346 is secured to the corner post 224 and the top cross rail 344. Therefore, the post 224 and the top cross rail 344 are pivotally mounted relatively to the longitudinal rail 212 for collapsing of this portion of the railing 95.

Referring particularly to Figures 24 and 33, counterbalance springs 293 are provided which tend to initiate and assist the movement of the railing 95 upwardly toward raised operative position. These springs are wound on end portions of the front pivot bar 221 which have inner end portions 371 secured in an intermediate tubular pivot bar portion 294. The ends of the springs 293 are secured in blocks 229¹ bolted to the pivot bar ends 221 and also in blocks 369 welded to the front face of the bottom cross frame rail 370. The end of the spring 293 secured in the block 369 abuts a block 228¹ adjacent the forward bottom pivot bracket 226. This block 228¹ is bolted to the block 369 by two bolts 374 which pass through the block 228¹ adjacently to the rear and front of the pivot pin ends 221.

When the locking lever 289, Figure 29, hereinafter fully described, is turned 90° from the position shown in dot-and-dash lines to a release position shown in full lines, the springs 293 throw the railing 95 upwardly into a partially raised condition whence it can readily be further and fully extended by workmen standing on the working floor 200 and using the handles 292, Figures 24 and 25, rearwardly extended from the rear upper cross rail 214.

The locking lever 289 includes a channel 290 secured to the outside face of the web of the longitudinal supporting channel 295 and having an upturned outwardly projected bottom lip 290¹. The flanges of the channel 290 are intersected by a rod 323 whose upper end projects upwardly from the top flange of the channel 290 and is secured to the body of the locking member 289, the locking member 289 being formed with a handle by means of which it may be turned through an arc of 90°, the dot-and-dash line position therefor shown in Figure 29 being that in which the handle portion is pressed or tramped down upon the floor 200 of the platform 8 and is a locking position, whereas the full line position shown in Figure 29 is when the locking member 289 is in releasing position. The locking member 289 is positively held in both positions by a spring 339 which is confined between the bottom flange of the channel 290 and a washer and nut combination secured to the lower threaded end of the rod 324. In locking position the member 289 bears upon a wear plate 266 secured to the top face of the longitudinal frame bar 212, this frame bar 212 being mounted upon the intermediate longitudinal frame bar 291, in the collapsed condition of the railing 95, the bar 291 being also formed with an angular wear plate 267, one leg of which bears upon the lower flange of the channel 290, Figure 29.

The positive locking of the railing 95 in upright position is effected by locking bars 215 which are pivoted at one end to brackets 357 secured to the top longitudinal rails 212, Figures 24, 25, and 26, the bars 215, when in locking position, extending rearwardly and downwardly and being engageable by locking members 341 formed on the lower end thereof with socketed members 216 secured to the bottom longitudinal frame members 296. When the locking bars 215 are detached and inoperative, they are swung on the pivot brackets 357 into the position clearly shown in Figures 25 and 32 where they are held in folded position on brackets 338 adjacently exterior of the outside face of the top longitudinal frame railing bars 212.

A further insulated foot lock assembly 343, Figure 24, is also provided having a locking pin 358, Figure 24. This lock assembly 343 prevents the accidental rotation of the railing 95.

Assuming that the railing 95 is in raised operative position shown in Figure 25, in order to collapse the same the bars 215 are removed from the sockets 216 and fastened in the brackets 338. The locking member 289 is in inoperative position shown in full lines in Figure 29 so the railing is moved forwardly by the handles 292, a partially collapsed condition being shown in Figure 26 and illustrating the relative pivotal movements of the several railing bars and posts until the railing is folded down into the collapsed condition on and projecting forwardly of the platform 200 shown in dot-and-dash lines in Figure 25. In this collapsed condition the railing side members lie exteriorly of the platform 200 and the supporting channels 295, as clearly shown in Figure 29. Then the locking member 289 is manually turned down or tramped down upon the working floor 200 and positively holds the longitudinal rails 212 and 291 in tight superimposed condition. Furthermore, the locking pin 358 of the foot lock 343 is moved into locking position. This collapsing action of the railing 95 has effected the compression of the counterbalance springs 293. When the railing 95 is in collapsed condition, provision is made for a nesting of the upper rear cross rail 214 and the intermediate rear cross rail 227 in the bottom longitudinal rails 296 by means of recesses 228 and 229, Figures 25 and 26, formed in the top portions of the rails 296 which respectively receive these rear cross rails 214 and 227.

When it is desired to raise the railing into operative position, the foot lock 343 and the locking member 289 are turned to non-locking positions which, under the ac-

tion of the counterbalance springs 293, results in throwing the railing 95 upwardly into partially raised position. Then the railing is moved upwardly and rearwardly by the handles 292 into almost fully raised operative position, the blocks 339, Figure 27, bending the springs 217 downwardly, the springs 217 thus forming safety members in that they make difficult the job of completely raising the railing 95 and thus direct attention to the necessity of swinging the locking bars 215 into locking position. This locking by the pivot bars 215 necessitates the complete raising of the railing 95 into working position.

What we claim is:

1. The combination in an erectable and collapsible railing, for use with and on a working platform of a utility truck tower, comprising a plurality of relatively pivoted railing parts including posts and railing bars forming a unitary fence-like structure bounding the working area of the platform, pivot means for securing the posts to the platform, releasable means for holding the railing in collapsed condition, locking means secured to the railing and cooperative releasable locking means secured to the platform, said locking means being adapted to interengage when the railing is in fully erected position to maintain the railing in such position, and means on the platform and means on the posts, one of said means being resilient, contacting each other to increasingly resist the rail-erecting movement as the railing approaches fully erected position whereby warning is thus given of the necessity of moving the railing to fully erected position to permit said interengaging locking means to become effective.

2. A railing characterized as in claim 1, in which said resisting means comprise plates secured to the platform, said plates having free spring end portions, and bosses secured to the posts, said bosses being adapted to engage and increasingly tension the spring end portions of said plates as the railing approaches fully erected position.

3. A railing characterized as in claim 1, in which the relatively pivoted railing parts include a plurality of

superimposed series of railing bars, and in which the interengaging locking means comprise bars respectively pivotally connected at one end to a topmost series of railing bars, and having opposite end locking members, and socketed members secured to the railing platform and engageable in the socket portions thereof by said locking members when the railing is erected to fully erected position.

4. A railing characterized as in claim 1, in which the railing is provided with handles suitable to effect the movement of the railing into fully erected position by manual effort applied to said handles, and in which there are resilient means cooperatively related to the rails and posts for initiating and assisting the movement of the railing toward fully erected position upon release of the holding means.
